UNITED STATES PATENT OFFICE.

HERBERT B. RAY, OF BRIDGEPORT, CONNECTICUT.

CAN-OPENER.

No. 809,527.

Specification of Letters Patent.

Patented Jan. 9, 1906.

Application filed April 8, 1905. Serial No. 254,497.

To all whom it may concern:

Be it known that I, HERBERT B. RAY, a citizen of the United States, residing at Bridgeport, county of Fairfield, State of Connecticut, have invented a new and useful Can-Opener, of which the following is a specification.

My invention has for its object to provide a simple and inexpensive can-opener that will open round cans of any size within reasonable limits by a single direct cut, which will be durable and practically impossible to get out of repair, which shall be neat and attractive in appearance, and which may be produced in quantities at such trifling cost as to enable it to be retailed at a price placing it within the reach of all.

With these ends in view I have devised the simple and novel can-opener, of which the following description, in connection with the accompanying drawings, is a specification, reference characters being used to indicate the several parts.

Figure 1 is a perspective illustrating the construction and operation of my novel can-opener; and Fig. 2 is a sectional view, on a greatly-enlarged scale, of the cutter detached.

My novel can-opener comprises two essential parts—to wit, a circular cutter and a carrier on which the cutter both rotates and slides freely. A denotes the carrier as a whole, and B the cutter. The carrier comprises a shank 10, a handle 11, and a prong 12, which may or may not be provided with a shoulder 13, and is preferably offset, as at 14. The shank, handle, and prong may be made from a single piece of wire, one end of which may be formed into a loop or into any convenient shape to form the handle, or, if preferred, a metallic or wooden handle may be attached to a straight shank in the usual or in any preferred manner. As the attachment of a separate handle to a shank is common in all classes of tools, it is not thought to require illustration.

The cutter comprises a cutting-disk, (indicated by 15,) a rest, (indicated by 16,) and a guide-disk, (indicated by 17.) These parts may be made separately and secured together or may be made in a single piece, as indicated in the drawings. The prong is shown as reduced from the stock of the shank. The central opening in the cutter, which I have indicated by 18, receives the shank freely, so that the cutter will both rotate and slide thereon. The inner face of the cutting-disk

is preferably made convex, as at 19, and the cutting edge is made to project slightly forward of the radial plane in order to prevent the cutting-disk from riding up on the edge of a cam when cutting out the top, the convexity being just sufficient to cause the cutting-disk to cut out the top of a can in a true circle just within the edge of a can; but without riding up on the edge. The shank, handle, and prong may be formed complete with the exception of the offsetting of the prong. In assembling the cutter is simply passed on the shank with the guide-disk toward the handle end, and then the prong is offset, which retains the cutter in place on the shank, permitting it to slide freely from the offset to the handle.

The operation is as follows: The prong is forced downward through the center of the top of the can, the passage of the shank very far into the can being prevented by the shoulder. The shank is then pressed down and the cutter placed in engagement with the edge of the can, the cutting-disk lying within the edge of the can and the guide-disk engaging the outer face of the edge of the can. The cutting-disk is then pressed down through the top of the can and the implement swung around by means of the handle, the cutter cutting its way through the top as the implement is moved around. The convex inner face of the cutting-disk and forward projection of the cutting edge prevent the cutting-disk from riding up on the top of the can, and the guide-disk retains the cutter in operative position, the rest lying in engagement with the edge of the can as the implement is swung around. By swinging the implement entirely around the entire top of the can will be cut out and may be removed, or, if preferred, the implement may not be passed quite around and a portion of the top not cut out, leaving that portion to serve as a hinge for the top, which may be lifted over out of the way to permit removal of the contents of the can, but without entirely detaching the top from the can. By using the implement in this manner the top may be cut out in a true circle close to the edge of the can and without leaving rough and jagged points of metal to mutilate and break up the contents of the can and to injure the hand of the operator.

Obviously the cutter B may be a separate article of manufacture and sale. If one cutter is worn out or damaged, another one may be substituted therefor. For instance, the

loop or handle 11 may be forced open enough to enable a worn cutter to be slid around the loop and removed and a new cutter placed on the shank 10 by a reversal of the movement 5 described.

Having thus described my invention, I claim—

1. A can-opener comprising a shank having a prong adapted to be forced through the center of a can-top and a cutter free to both rotate and slide on the shank and comprising a cutting-disk, a rest adapted to engage the edge of a can and a guide-disk adapted to engage the outer face of a can, the relative sizes 15 of said disks being such as to permit the guide-disk to project below the plane of the top edge of the can when the cutting-disk is severing the top of the can.
2. A can-opener comprising a shank having a prong adapted to be forced through the center of a can-top and a cutter free to both rotate and slide on the shank and comprising a cutting-disk convex on its inner face and having a forwardly-projecting cutting edge,

for the purpose set forth, a rest to engage the 25 edge of a can and a guide-disk to engage the outer face of said can to retain the cutter in operative position, the relative sizes of said disks being such as to permit the guide-disk to project below the plane of the top edge of 30 the can when the cutting-disk is severing the top of the can.

3. The cutter B comprising a rotary cutting-disk, a rest adapted to engage the edge of a can and a guide-disk adapted to engage 3. the outer face of a can, said disks and rest being integral, and the relative sizes of said disks being such as to permit the guide-disk to project below the plane of the top edge of the can when the cutting-disk is severing the 4. top of the can.

In testimony whereof I affix my signature in presence of two witnesses.

HERBERT B. RAY.
